TRAP FOR TRAPPING CERTAIN CRUSTACEANS AND THE LIKE

Frank A. Torngren, 47 West St.,
Attleboro, Mass. 02703

Filed Jan. 31, 1973, Ser. No. 328,315

Term of patent 14 years

Int. Cl. D22—06

U.S. Cl. D22—18

FIG. 1

FIG. 2

FIG. 3

FIG. 4

FIG. 5

FIG. 1 is a front plan view of a trap for trapping certain crustaceans and the like;

FIG. 2 is a top plan view of the FIG. 1 apparatus;

FIG. 3 is a bottom plan view of the FIG. 1 apparatus;

FIG. 4 is a right side plan view of the FIG. 1 apparatus;

FIG. 5 is a left side plan view of the FIG. 1 apparatus; and

FIG. 6 is a perspective view of the back, top and right sides of the trap shown with netting broken away for purposes of clarity of illustration.

I claim:

The ornamental design for a trap for trapping certain crustaceans and the like, substantially as shown and described.
